(57) **CLAIM**

The ornamental design for a roll towel dispenser lockout, as shown and described.

DESCRIPTION

FIG. 1 is a perspective view of a roll towel dispenser lockout incorporating our new design, viewed from in front of, above, and from the left side thereof;

FIG. 2 is an exploded perspective view thereof viewed from in front of, above, and the left side;

FIG. 3 is an exploded perspective view of thereof viewed from in front of, above, and the right side;

FIG. 4 is a left side elevation view thereof;

FIG. 5 is a right side elevation view thereof;

FIG. 6 is a front elevation view thereof;

FIG. 7 is a rear elevation view thereof;

FIG. 8 is a top plan view thereof; and,

FIG. 9 is a bottom plan view thereof.

The broken lines shown in the drawings represent portions of the roll towel dispenser lockout that form no part of the claimed design.
